Primary Examiner — R. Johnson(74) *Attorney, Agent, or Firm* — Daniel M. Cohn; Howard M. Cohn(57) **CLAIM**

The ornamental design for an adjustable saxophone chest strap, as shown and described.

DESCRIPTION

FIG. 1 is a perspective view of an adjustable saxophone chest strap showing my new design;
 FIG. 2 is another perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof; and,
 FIG. 8 is a bottom plan view thereof.

The broken lines in the figures are for the purposes of illustrating portions of the adjustable saxophone chest strap, which form no part of the claimed design.
